(57) **CLAIM**

The design for an automobile, as shown and described.

DESCRIPTION

FIG. 1 is a front left side perspective view of an automobile;

FIG. 2 is a rear left side perspective view thereof;

FIG. 3 is a left side view thereof;

FIG. 4 is a right side view thereof;

FIG. 5 is a front view thereof;

FIG. 6 is a rear view thereof; and,

FIG. 7 is a top plan view thereof.

The broken lines in the drawings illustrate portions of the automobile that forms no part of the claimed design.
